CLAIM

The ornamental design for self-supporting pouch dressing, substantially as shown and described.

DESCRIPTION

FIG. 1 is perspective view of a conformable dressing showing our new design;

FIG. 2 is a top plan view thereof;

FIG. 3 is a bottom plan view thereof;

FIG. 4 is a right side elevational view thereof, the left side being a mirror image; and,

FIG. 5 is a front elevational view thereof, the rear being a mirror image.

The broken line drawing in all figure views is for illustrative purposes only, and forms no part of the claimed design.
